J. CUTHBERT.
HINGE CONSTRUCTION.
APPLICATION FILED OCT. 12, 1915.

1,206,817.

Patented Dec. 5, 1916.

UNITED STATES PATENT OFFICE.

JOHN CUTHBERT, OF CHICAGO, ILLINOIS.

HINGE CONSTRUCTION.

1,206,817.

Specification of Letters Patent. Patented Dec. 5, 1916.

Application filed October 12, 1915. Serial No. 55,403.

To all whom it may concern:

Be it known that I, JOHN CUTHBERT, a citizen of the United States, residing at Chicago, in the county of Cook and State of Illinois, have invented certain new and useful Improvements in Hinge Construction, of which the following is a specification.

My invention relates to hinges.

The general object of my invention is to provide an improved hinge.

A more specific object is to provide a hinge for a flush door or closure which is not visible from the flush or outside of the receptacle.

Other and further objects of my invention will become readily apparent, to persons skilled in the art, from a consideration of the following description when taken in conjunction with the drawings, wherein:—

Figure 1 is a section taken on line 1—1 of Fig. 2 showing a part of the receptacle structure and a flush door hinged thereto, the dotted lines showing the open position of the door or closure. Fig. 2 is a rear elevation.

Fig. 3 is a section taken on line 3—3 of Fig. 2. Fig. 4 is a fragment of an interior part of the structure showing one of the hinge members. Fig. 5 is a complementary hinge member to be attached to the door.

In all the views the same reference characters are employed to indicate similar parts.

I have shown my hinge construction in connection with a metal cabinet for containing panel board fittings, and the like, for electric circuits. It is obvious, however, that it may be used for many other similar structures; in fact with any sort of a container or receptacle where it is desired that the door or closure should be even or flush with the outside surface thereof, and without showing the hinges on the outside of such structure.

6 is the outside wall of a cabinet or other structure to which the flush door 7 is hinged. 8 is a jamb plate that is inseparably attached to the wall 6 as by spot welding or by rivets and bridges the margin of the opening or the joint where the door is hinged, thus providing a rabbet between said plate and the inner edge of the doorway and serving as a jamb. A portion of the plate is downturned, or inturned, as at 9 to form members of the hinge. Each inturned portion is provided with a segmental opening 10 which extends circumferentially or with substan-

tially uniform radius from the center of a groove 11.

The plate 8 is provided with an integral inwardly deflecting portion 8' which forms a partition dividing the receptacle into two compartments, the inner one having as a base a panel board and the other, outer, annular compartment inclosing the hinges and wiring connections and concealing them from view when the door is open. A hinge member 12 projects beyond the edge of the door and is downturned at its edge, as at 13, to provide flanges to give it strength and is provided on the edges at one of its ends with lateral projections 14—14 to enter the slots 10 of the confronting plates. The main body part of the member 12 is sufficiently wide to move freely between the downturned hinge members 9—9 of the plate 8. The projecting hinge member 12 is to be attached to the door 7, by spot welding, rivets or the like, and in such relation that the projections 14 will sweep through the segmental slots 10 in the plates 8 when the edge 7' of the door 7 enters the groove 11.

A spring 15 is attached to the door 7 to yieldingly hold the door in closed position, as shown in Fig. 1. In the illustrated form it is secured at one end to the outer end of plate 12 and is bent in a U to lie with its other end bearing against the inner face of wall 8'.

When the door 7 is open, as shown in dotted lines in Fig. 1, the edge 7' will enter the parallel groove or depression 11 in the jamb plate 8 while the projections 14 from the door will sweep through the slots 10 and be guided therein and serve to hold the door in its position when open. The spring 15 will close the door, when it is released, to be returned into the position shown in Fig. 1.

Without the groove 11, in the jamb plate 8, the edge 7' of the door would ride over the adjacent edge of the wall 6 when the door is being opened. The groove 11 serves as a turning point for the door and being the radial point for the slots 10, the projections 14 of the hinge member 12 move freely in the segmental slots without interposing any material resistance to the movement of the door.

It is, of course, manifest that my hinge mechanism may be applied to other structures or receptacles than cabinets and their closures.

It is further understood that many changes may be made in the general form, arrangement, configuration and disposition of the parts within the scope of the appended claims.

Having described my invention, what I claim is:

1. A closure hinge for a receptacle comprising a jamb plate secured to the inner side of the receptacle wall and having a groove parallel with and bridging the joint between said wall and receptacle closure at the hinged side; a closure, flush with the wall when closed, with its hinged edge overlying said groove; a hinge member extending from the closure beyond adjoining edges and a stationary hinge member secured to the inside of the wall, serving as a guide when the edge of the closure is within said groove.

2. A closure hinge for a receptacle comprising a jamb plate secured to the inner side of the receptacle wall and having a groove bridging the joint between said wall and receptacle closure at the hinge side, and parallel with said joint; a closure, flush with the wall when closed, with its hinged edge overlying said groove; a hinge member extending from the closure beyond adjoining edges and a hinge member comprising two confronting stationary plates secured to the inside of the wall serving as guides for the coöperating closure member when the edge of the closure is within said groove.

3. A closure hinge for a receptacle, comprising a jamb plate secured to the inner side of the receptacle wall and having a groove bridging the joint between said wall and receptacle closure at the hinged side and parallel with said joint; a closure flush with the wall when closed, with the hinged edge partially overlying said groove; a hinge plate member having lateral projections secured to the closure and extending beyond adjoining edges and a fixed hinge member comprising two confronting parallel plates secured to the inside of the wall and having segment shaped perforations into which the projections of the coöperating hinge member extend, serving as guides therefor when the edge of the closure is within said groove.

4. A closure hinge for a receptacle opening comprising a wall, to an edge of which a closure is to be hinged; a jamb plate secured to the inner side of the wall and extending into the closure opening beyond the meeting edge of said closure and wall to bridge the joint by thereby providing a rabbet; a closure, flush with the wall on the outside, when closed; a part projecting into the receptacle from the inner edge of said plate; and hinge members secured respectively to said closure and wall on the

inside of said receptacle and lying at all times inside of the rabbet.

5. A closure hinge for a receptacle opening comprising a wall, to an edge of which a closure is to be hinged; a jamb plate secured to the inner side of the wall and extending into the opening beyond the meeting edge of the closure and wall; a closure flush with the wall on the outside when closed and adapted to swing about its edge bearing on the jamb plate as an axis; a projecting hinge member carried on the inner side of the closure adjacent said edge; and an arcuate guide carried on the inner face of the wall and engaged by said projecting hinge member.

6. A closure hinge for a receptacle opening comprising a wall, to an edge of which a closure is to be hinged; a jamb plate secured to the inner edge of the wall and extending into the opening beyond the meeting edge of the closure and wall; a closure flush with the wall on the outside when closed and adapted to swing about its edge as an axis; a projecting hinge member carried on the inner side of the closure adjacent said edge; an arcuate guide carried on the inner face of the wall and engaged by said projecting hinge member; and means for resiliently holding said closure edge in contact with the adjacent wall edge.

7. A closure hinge for a receptacle opening comprising a wall, to an edge of which a closure is to be hinged; a jamb plate secured to the inner side of the wall and extending into the opening beyond the meeting edge of the closure and wall; a closure flush with the wall on the outside when closed and adapted to swing about its edge as an axis; a projecting hinge member carried on the inner side of the closure adjacent said edge and extending through an opening in the jamb plate to the inner side thereof; an arcuate guide carried on the inner face of the wall and engaged by said projecting hinge member; and a spring engaging the projection to maintain the said closure edge in resilient contact with the adjacent wall edge.

8. A closure hinge for a receptacle opening comprising a wall, to an edge of which a closure is to be hinged; a jamb plate secured to the inner side of the wall and extending into the closure opening beyond the meeting edge of said closure and wall to bridge the joint; a closure, flush with the wall on the outside when closed; a part projecting into the receptacle from the inner edge of said plate; a movable hinge member having lateral projections secured to the closure and extending beyond the closure; and a fixed hinge member comprising two confronting parallel arcuate guides secured to the inside of the receptacle wall and engaged by the said lateral projections.

9. A closure hinge for a receptacle opening comprising a wall, to an edge of which a closure is to be hinged; a jamb plate secured to the inner side of the wall and extending into the closure opening beyond the meeting edge of said closure and wall to bridge the joint; a closure flush with the wall on the outside when closed; a part projecting into the receptacle from the inner edge of said plate; a movable hinge member having lateral projections secured to the closure and extending beyond the closure; a fixed hinge member comprising two confronting parallel arcuate guides secured to the inner

face of the wall and engaged by the said 15 lateral projections; and a leaf spring secured to said movable hinge member and engaging the inner side of the inwardly projecting part to resiliently hold the closure edge in contact with its adjacent wall edge. 20

In testimony whereof I hereunto set my hand in the presence of two subscribing witnesses.

JOHN CUTHBERT.
